JOHN C. KREPS, JR., OF CAMDEN, GEORGE M. MARSH, OF GLOUCESTER, AND WILLIAM C. LUTZ, OF RUNNEMEDE, NEW JERSEY.

HUMIDIFIER.

Application filed May 6, 1926. Serial No. 107,115.

Our invention relates to a new and useful improvement in humidifiers and has for its object to so construct a device of this description that it may be readily brought into coaction with a source of heat, such as gas or oil stoves, in such manner as to provide for the products of combustion or the heated air disseminated from said source of heat taking up a relatively large percentage of moisture.

A further object of our invention is to provide means for conveniently securing the humidifier to stoves of usual construction, and in the case of stoves where the upper portions thereof are hinged, to provide for the turning down of this upper portion to gain access to the oil reservoir or gas burner.

With these and other ends in view, this invention consists in the details of construction and combination of elements herein-after set forth and then specifically designated by the claims.

In order that those skilled in the art to which this invention appertains, may understand how to make and use the same, we will describe its construction in detail, referring by numerals to the accompanying drawings forming a part of this application, in which:

Fig. 1, is a side elevation of an oil stove of usual construction having our improved humidifier applied thereto.

Fig. 2, is an enlarged plan view of the sectional reservoir of the humidifier.

Fig. 3, is an enlarged detailed sectional view showing the means for locking the sections of the reservoir in place, and also showing the upper portion of one of the stay rods upon which the stationary section of the reservoir is adjustably mounted.

Fig. 4, is a view similar to Fig. 3, showing upper portion of the other stay rod and the means by which it is utilized to support the stationary section of the reservoir and hinge the swinging section.

Fig. 5, is a section on the line 5—5 of Fig. 2.

In carrying out our invention as shown in Figs. 1 to 5, inclusive, 1 represents an oil stove of any ordinary design, to which is attached the supporting blocks 2, by means of the bolts 3, which pass through certain of the holes 4, usually found in this character of stove, being utilized for admitting air to the burner, and these blocks

have projecting upward therefrom the stay rods 5 and 6, the upper ends of which are threaded, for the purposes as hereinafter explained.

7 and 8 represent the two sections of a reservoir, each section being approximately the same size, the section 7 carrying the lugs 9 at one end thereof, said lugs being adapted to fit over the upper end of the stay rods 6, and being adjusted thereon by the nuts 10 and 11 threaded upon this rod.

One end of the section 8 of the reservoir carries the lugs 12 which are also adapted to fit over the upper end of the stay rods 6, and are intended to be positioned between the lugs 9.

The opposite end of the said section 8 of the reservoir is provided with the lugs 13, through which the upper end of the stay rod 5 passes, and this stay rod has threaded thereon the nuts 14 and 15 for adjusting the vertical position of this end of the section 8.

These lugs 13 also have holes therethrough for the passage of the locking pin 16, which is also adapted to pass through the lugs 17 carried by one end of the section 7 as clearly shown in Fig. 3.

By this arrangement both sections of the reservoir will be supported by the stay rods, the section 8 being stationary while the section 7 may be swung open upon the stay rod 6 by the removal of the locking pin 16, and this swinging open of the section 7 will permit the swinging open of the upper portion of the stove for access to the lamp or burner.

Each section of the reservoir is of the shape in cross section clearly shown in Fig. 5, having the water space 18 therein, and also showing the baffle flange 19, which extends upward and inward to deflect the moisture arising from the water in the reservoir, and also to baffle the heated air or products of combustion passing through the usual perforations in the stove casing, and these baffle flanges have a series of holes 20 therein so as to facilitate the circulation of the hot air, products of combustion and moisture.

From the foregoing description it will be seen that our improved humidifier may be readily attached to the ordinary form of oil or gas stove, especially the former, without any alteration of the stove and when so at-

tached, the reservoir may be adjusted into the proper relative position to the outgoing of the products of combustion or heated air to efficient absorption of moisture, for modifying the products of combustion and rendering the heated air more healthful and more agreeable to the occupants of the room in which the stove is being used.

Of course we do not wish to be limited 10 to the exact details of construction as herein shown as these may be varied within the limits of the appended claims without departing from the spirit of our invention.

Having thus fully described our invention, 15 what we claim as new and useful is:—

1. In combination with a heating element, a humidifier comprising a sectional reservoir, each of said sections having a baffle flange, said flanges being perforated, and 20 means for mounting the sections of reservoir.

2. In combination with the casing of a stove, two blocks secured to said casing, two stay rods carried by said blocks, a reservoir comprising a stationary section and a 25 swinging section supported upon said stay rods, means for locking the swinging section in its normal position relative to the stationary section and means for adjusting the sections vertically.

3. A humidifier for oil or gas stoves comprising two sections, means for supporting one of said sections as a stationary element,

means for pivoting the other section to the stationary section and means for locking the pivoted section into normal relation with 35 the stationary section.

4. The herein described combination of a stationary section, means for adjustably mounting said stationary section upon a stove, a swinging section pivoted to the stationary section, and means for normally holding the swinging section in its closed position.

5. In a reservoir for humidifiers, a stationary section, lugs carried by each end of 45 said section, a swinging section, lugs carried by each end of said swinging section, the lugs upon one end of the stationary section adapted to interlock with the lugs upon one end of the swinging section, a stay rod 50 passing through said interlocking lugs; lugs carried by the opposite end of the swinging section and adapted to interlock with the lugs upon the opposite end of the stationary section, and a pin adapted to pass through 55 holes formed in the last named interlocking lugs for holding the swinging section in its normal closed position, relative to the stationary section.

In testimony whereof, we have hereunto affixed our signatures.

JOHN C. KREPS, JR.
GEORGE M. MARSH.
WILLIAM C. LUTZ.
